CLAIM

The ornamental design for an electric evaporator device, as shown and described.

DESCRIPTION

FIG. 1 is a right side and front perspective view of an electric evaporator device showing our new design;

FIG. 2 is a right side view thereof;

FIG. 3 is a front view thereof;

FIG. 4 is a rear view thereof;

FIG. 5 is a top plan view thereof; and,

FIG. 6 is a bottom plan view thereof.

The broken line showing of environmental structure in FIGS. 1, 2, and 4-6, is for illustrative purposes only and forms no part of claimed design.
